UNITED STATES PATENT OFFICE

170,636

CADDY CART

Frank A. Gastright, Fort Lauderdale, Fla.

Application May 11, 1953, Serial No. 24,946

Term of patent 14 years

(Cl. D14—3)

To all whom it may concern:

Be it known that I, Frank A. Gastright, have invented a new, original, and ornamental Design for a Caddy Cart, of which the following is a specification, reference being had to the accompanying drawing, forming a part hereof.

Fig. 1 is a side elevation of the caddy cart;

Fig. 2 is a plan view;

Fig. 3 is a rear elevation; and,

Fig. 4 is a front elevation, showing my new design.

I claim:

The ornamental design for a caddy cart, as shown.

FRANK A. GASTRIGHT.
